HANDBAG

Aaron Landis, Elizabeth, N. J.

Application October 18, 1937, Serial No. 169,529

5 Claims. (Cl. 150—36)

This invention relates to handbags.

One object of the invention is to provide a handbag having an improved internal secret pocket concealed by a flap-like lining member.

5 Another object of the invention is to furnish a handbag in which a concealing flap lining member for a secret pocket is so arranged relative to the bag body, in respect to size or proportion or in relation to infolding gussets as not to be noticeable when the handbag is opened.

10 Another object of the invention is the provision of a handbag having a flap closure from which depends in utmost uniformity a concealing lining member for a secret pocket in the bag body so that the lining member appears to be merely a part of the flap lining.

15 Another object of the invention is to construct a handbag having a secret pocket in the body thereof, and a lining member connected to the handbag flap to provide a secret pocket in register with the first secret pocket with the lining member depending to conceal both, whereby elongated articles may be disposed and hidden from view.

20 Another object of the invention is the provision of a lining member to conceal a secret pocket wherein the lining member depends into the bag body and is reliably so retained by a weighting container or by a resilient strip element that expands into the bag body, or both.

25 Another object of the invention is to furnish a secret pocket accessible for small articles from within the bag body and accessible for large articles from the outside of the bag body.

30 Another object of the invention is to provide a bag body having a secret pocket provided with a relatively concealed closable bottom opening, with the side and end walls being simple and uniform in structure.

35 Another object of the invention is to provide a handbag having slide fastener means for the top and bottom openings of pockets, arranged to operate in different directions for the close packing of articles in the pockets as a result of different degrees of gusset expansion at different parts of the pockets.

40 A further object of the invention is to provide a handbag having few and simple parts, and which is durable and reliable, inexpensive to make, convenient, neat, compact and efficient in use.

45 Other objects and advantages of the invention will become apparent as the specification proceeds.

50 55 With the aforesaid objects in view, the inven-

tion consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is an isometric sectional view of one-half of a handbag embodying the invention.

Figs. 2 and 3 are sectional views taken respectively on lines 2—2 and 3—3 of Fig. 1.

Fig. 4 is a fragmentary view of a bottom portion of the handbag.

Fig. 5 is a sectional view on line 5—5 of Fig. 4.

Fig. 6 is a view in end elevation with parts removed showing the handbag in open position and with the secret pocket exposed.

Fig. 7 is a perspective view of a modified handbag.

Fig. 8 is an end view thereof with a part removed.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a handbag embodying the invention. The same includes a bag body comprising side walls 11, 12, opposite end walls or gussets 13, and a bottom wall 14, interconnected to provide a compartment open at the top. This top opening may be closed by a flap 15 which is an extension of the side wall 12 and is foldable to closed position in the usual manner.

Within the bag body is a lining which is folded at the bottom at 16 to provide upward extending side wall sections 17, 18. The section 17 is connected to the wall 11 as at the top thereof at 19 and at the ends thereof at 20. The section 18 is connected to the wall 12 at the ends thereof as at 21. Further the bottom portion 16 is connected to the gussets 13 at the bottom ends thereof as at 22. Otherwise the lining is free or sufficiently so to furnish with the wall 12, a secret pocket 23, and with the wall 11, a secret pocket 24. Of these the former may open upwardly, the latter downwardly as shown.

Connected to the flap at the end as at 25 is a lining member 26 which is also connected to the sides of the flap as at 27 to thus provide a secret pocket 28 in register with the secret pocket 23.

5 The connection 27 terminates at the mouth of the latter, and the lining member 26 is formed with an integral lining portion 29 forming an extension which drapes down freely over and conceals the secret pocket 23. The lining element 10 29 extends almost to the bottom 16 so as to be concealed in the bag, and extends substantially from one to the other of the end walls 13.

The gussets 13 are considerably infolded so as to overlie and hold and conceal the side edges of the lining member 29.

The lining member 29 may be weighted to retain its position as by pocket forming wall 30, or by a purse 31 or both. The wall 30 may be secured to the lining member 29 as at 32, and the purse 31 may be suitably secured to the wall 30. Both the purse and the pocket formed by the wall 30 open upwardly for ready access at the handbag mouth.

To retain the lining member 29 longitudinally taut, a stiffener or resilient strip element 33 may be connected along the lower edge of the lining member. For example, an extension of the latter may be upwardly folded at 34 and stitched at 35 to form a hem retainer for the element 33 and to form the wall 30 and the bottom for the pocket thereof. The hem 34 may enclose the ends of the element 33, with the latter disposed in end abutment with the gussets 13 and under the folds thereof.

35 A closure means may include a snap fastener socket 36 secured to the wall 11, and a snap fastener head 37 secured to the flap 15 or the lining 26 thereof. If desired, a snap fastener socket 38 may be fixed to the lower edge part of the
40 lining member 29.

The bottom 16 may be in substantial contact with the bottom 14 so that the pocket 23 may be substantially closed at its lower end, if desired.

The bottom wall 14 may have a longitudinal opening closed by a slide fastener 39. When the latter is opened, access is had to the secret pockets 23, 24, and 28. To conceal the means 39, the side walls 11, 12 may have downward extending portions 40 which extend below the slide fastener and tend to conceal the same. These portions 40 lie below the connections at 41 between the stringers or bottom wall 14 and the side walls 11, 12. When the slide fastener is closed, it closes snugly over the free edges of the gussets to close the bottom of the bag.

The manner of using the handbag will now be briefly described. In the position shown in Fig. 1, the purse, the pocket at 30, and the main pocket can be readily and conveniently used in the usual manner. The lining member 29 drapes down uniformly from the flap 15 and as a part thereof. It extends almost to the bottom and from end to end. It may be held even by the stiffener 33, or by the weighting containers 30, 31 or both. The infolded gussets 13 help to conceal the side edges of the lining member. Thus there is nothing to suggest a secret pocket or anything else unusual about the bag structure. When access to the secret pocket 23 is desired, the lining member 29 is swung outwardly. The element 33 may be flexed to facilitate the movement. In folding the lining member 29 on itself, it assumes the position shown in Fig. 6. This folding causes the pocket 30 to be closed against the loss of articles. The fasteners 37, 38 may

be connected to keep the mouth of the secret pocket 23 free and open. Reverse movements return the handbag to the position of Fig. 1, and the flap 15 may be closed and secured at the fasteners 36, 37. When thus closed, the handbag may be inverted, and the slide fastener 39 opened for access to the secret pockets 23, 24 and 28.

Small articles and papers may be placed in the secret pocket 23 by raising the lining member 29 as above described. For large or bulky articles, the slide fastener 29 is used. In this manner, the secret pockets 23, 28 may form a single very large secret pocket, in which documents may be inserted flatwise and protectively folded by folding the flap 15 to closed position. A still larger object may be inserted by folding one end portion thereof into the pocket 24. If preferred, the pocket 23 may be closed at its bottom, so that only the pocket 24 shall be communicable with the slide fastener. For this purpose, the walls 12 and 18 may be connected together.

As already stated, the slide fastener 39 is concealed between the button extensions 40.

In Figs. 7 and 8 is shown a handbag 45 according to a modified form of the invention. This is generally like the handbag 10, except that the flap 15 is omitted and a slide fastener 46 is used in place thereof. In that case, the lining member 29a is connected to the side wall 12a at 47 in a conventional manner to thus conceal the secret pocket 23. The top and bottom slide fasteners 39 and 46 are of the usual type and each is preferably permanently closed at one end as at 48. However, in the device 45, these slide fasteners are operative in opposite directions, as will now be described. Fig. 7 is diagrammatic with parts omitted.

In Fig. 7, the handbag is shown with both slide fasteners wholly opened. It will now be seen that with the upper slide fastener opening toward the left, the upper right end of the upward opening pocket of the handbag can be fully expanded at the right gusset 13. With the lower slide fastener opening toward the right, the lower left portion of the downward opening pocket can be fully expanded by expansion of the left gusset 13. This arrangement permits the pockets, which lie alongside of each other, to be fully packed with articles without causing undue bulging at any point of the bag. In practice, only one slide fastener is open at one time but the same results follow. Otherwise, the construction and mode of use of the bag 45 is like that of the bag 10.

It will be appreciated that a secret pocket of the type herein mentioned may be provided at either side of the handbag, and that the invention may also be applied to framed handbags.

I claim:

1. A handbag including a bag body comprising side and end walls and a bottom wall, the bag body having a top opening, an internal wall member having a bottom fold providing side wall sections one of which is connected to one side wall along the top and the ends of the latter and forming a downward opening secret pocket therewith, the other wall section being connected to the ends of the other side wall and being otherwise free of the latter to provide an upward opening secret pocket therebetween, a flap-like lining member connected to the bag body to depend over and conceal the secret pocket, the lining member being removably extended into the bag body, and the said bottom wall having

means providing a closable opening communicating with both of said secret pockets.

2. A handbag according to claim 1, wherein the bottom of the internal wall member is in engagement with said bottom wall to form an openable closure separating the upward and downward opening secret pockets.

3. A handbag comprising a bag body, the latter having side and end walls providing therebetween a main compartment open at the top of the bag body, one of said side walls having an upward opening secret pocket therein and having an upward extension constituting a closure flap for said top opening, above the secret pocket, and a lining member connected to said flap along the sides and end thereof, said lining member having an extension lining portion depending over the secret pocket into the main compartment into relative proximity to the bottom thereof, said lining member being substantially of the length of the distances between said end walls, and means comprising a pair of elements for releasably connecting the lining member to the flap so that the lining member is held in outwardly swung position by the flap when the latter is in open position, one of said elements being on the flap, and a third element on the bag body releasably cooperative with the element on the flap to hold the latter in closed position.

4. A handbag including a bag body compris-

ing side and end walls and a bottom wall, the bag body having a top opening, an internal lining means connected to the bag body substantially along said top opening and having a bottom fold adjacent to said bottom wall, said lining means providing lining sections forming side pockets between the sections and the adjacent respective side walls of the bag body, and said bottom wall having means including an openable closure for access to both of said side pockets, one of said lining sections affording a secondary top opening for one of said side pockets, and the lining means including a depending lining element folding downward into the bag body in the manner of a flap to overlie and conceal said secondary top opening of said side pocket.

5. A handbag including a bag body having side walls and end walls having gussets extending substantially the full depth of the bag body, a lining means in said bag body affording an upward opening pocket means, a depending lining member secured to the bag body extending over said pocket means to conceal the top opening thereof so as to provide a secret pocket, said bag body having a bottom wall having means providing a closable opening communicating with the secret pocket means, and the infolded portions of the end gusset walls serving to overlie and hold the said lining member in its concealing position.

AARON LANDIS. 30
